(57) **CLAIM**

The ornamental design for a computer housing, as shown and described.

DESCRIPTION

FIG. 1 is a perspective view of a computer housing showing my new design, and shows the front, top and left side, the bottom of the housing being plain and unornamented, FIG. 2 is a top plan view thereof, FIG. 3 is a front elevation thereof, FIG. 4 is a left side elevation thereof, the right side elevation being a mirror image of the left side, FIG. 5 is a rear elevation thereof, FIG. 6 is a perspective view similar to FIG. 1 of a second computer housing showing my new design, the right side elevation, front elevation and rear elevation being the same as the corresponding views of the computer housing shown in FIG. 1 and the bottom being plain and unornamented, FIG. 7 is a perspective view similar to FIG. 1 of a third computer housing showing my new design, the right side elevation, front elevation and rear elevation being the same as the corresponding views of the computer housing shown in FIG. 1 and the bottom being plain and unornamented; and, FIG. 8 is a perspective view similar to FIG. 1 of a fourth computer housing showing my new design, the right side elevation, front elevation and rear elevation being the same as the corresponding views of the computer housing shown in FIG. 1 and the bottom being plain and unornamented.
